UNITED STATES PATENT OFFICE.

HARRY D. LATHROP AND WALTER H. PAULSON, OF CHICAGO, ILLINOIS; SAID PAULSON ASSIGNOR TO SAID LATHROP.

SOLUTION PROCESS.

Application filed August 23, 1922. Serial No. 583,719.

To all whom it may concern:

Be it known that we, HARRY D. LATHROP and WALTER H. PAULSON, citizens of the United States, and residents of the city of Chicago, county of Cook, and State of Illinois, respectively, have invented certain new and useful Improvements in Solution Processes, of which the following is a specification.

Our invention relates to a solution process, and more particularly concerns the making of a solution of washing fluid to be introduced into a tank or the like to be used for the purpose of washing bottles or similar articles, and has for its principal object the provision of an improved method of making a solution of washing fluid which will be highly efficient in use.

Other objects will appear hereinafter.

The invention consists in the combinations and arrangements of parts hereinafter described and claimed.

The invention will be best understood by reference to the accompanying drawings forming a part of this specification, and in which—

Fig. 1, is a top plan view of the invention; and

Fig. 2, is a vertical sectional detail view taken substantially on line 2—2 of Fig. 1.

In carrying the objects of the invention into effect, 5 indicates a tank or mixing receptacle having plug 6 for the purpose of draining the receptacle when occasion requires. Pipe 7, is a water supply pipe, passage therethrough being controlled by valve 8, of suitable construction. Pipe 7 is in communication with a horizontal pipe 9, located above tank 5 and extending approximately, half-way across. Communicating with pipe 9 is a depending lead pipe 10 having an inverted dish-shaped splasher 11, preferably arranged an applicable distance above the bottom 12 of tank 5, the distance being determined when the device is in use.

A lead-off pipe 13 communicates with tank 5 and is positioned adjacent to the top edge of the wall 14 of tank 5 and communicates with an ejector (not shown) of suitable construction or with the tank (not shown) into which it is desired to drain the solution of washing fluid.

In the present instance we prefer to fill the tank with soda to a level indicated by dotted line 15, the level of the soda solution

being determined by the operator of the machine and it is to be thoroughly understood that this level of soda varies.

In use, the valve is opened permitting passage of water (clear water preferred) to flow through pipes 7, 9 and 10 and be ejected through splasher bowl 11. As the water is ejected through splasher bowl 11, the force of the water, which varies, stirs up the soda, at the bottom of the tank 5, and gradually filters to the top of the soda where the solution is taken off by the lead-off pipe 13 to its destination.

In our improved method of making a soda solution, the soda will last longer, and retain a strong solution. In the old method of making a soda solution, the soda heretofore had been poured directly into the washing fluid tank and dissolved in the water therein. This method is costly and a large percentage of the pure soda is wasted, being carried off with the solution through the lead-off pipe to its destination. In our method the solution is carried from the mixing tank through the lead-off pipe to its destination and very little if any at all of the soda, that is the solid particles of soda, is carried away by the solution.

While we have illustrated the value of the invention by dissolving the soda to make a soda solution, it is to be thoroughly understood that any soluble substance adapted for the purpose can be used as well.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having described our invention, what we claim as new and desire to secure by Letters Patent is:

1. A method of making a solution of washing fluid consisting in partially filling a tank, provided with an overflow, with a soluble substance, directing water to the bottom of said tank to emerge and spread at the bottom of said substance and permit the water to dissolve said substance and filter to the top thereof and pass through said overflow.

2. A method of making a solution of washing fluid consisting in partially filling a tank, provided with an overflow, with soda, directing water to the bottom of said tank and soda to permit the water to dissolve said soda and filter to the top thereof and pass through said overflow.
3. A method of making a solution of washing fluid consisting of filling a tank, provided with an overflow, with a soluble substance, directing water to the bottom of said tank through a supply pipe having a splasher plate at its discharge end embedded

near the bottom of said substance for spreading the water to agitate and dissolve 15 said substance and filter to the top thereof, and pass through said overflow.

In testimony whereof we have signed our names to this specification in the presence of two subscribing witnesses.

HARRY D. LATHROP.
WALTER H. PAULSON.
